Des. 213,689
Patented Apr. 1, 1969

213,689

COMBINATION CASKET AND BURIAL VAULT

Wesley M. Chandler, St. Paul, and Bernard T. Juba, White Bear Lake, Minn., assignors to Wilbert, Inc., Forest Park, Ill., a corporation of Illinois

Filed Mar. 20, 1968, Ser. No. 11,067

Term of patent 7 years

Int. Cl. D31

U.S. Cl. D19—1

FIG. 1 is a perspective view of a combination casket and burial vault embodying our new design;

FIG. 2 is a side elevational view as seen from the left side in FIG. 1;

FIG. 3 is an elevational view of the end opposite to that seen in FIG. 1.

FIG. 4 is a top plan view of our new design.

We claim:

The ornamental design for a combination casket and burial vault, substantially as shown.
